UNITED STATES PATENT OFFICE.

THOMAS JAMES MURPHY, OF NEW YORK, N. Y., ASSIGNOR OF ONE-HALF
TO ROGER POTTER, OF SAME PLACE.

TRIPOD FOR ROCK-DRILLING MACHINES.

SPECIFICATION forming part of Letters Patent No. 383,064, dated May 15, 1888.

Application filed October 14, 1887. Serial No. 252,378. (No model.)

To all whom it may concern:

Be it known that I, THOMAS JAMES MURPHY, a citizen of the United States, and a resident of the city of New York, in the county and State 5 of New York, have invented a new and useful Improvement in Tripods for Rock-Drilling Machines, of which the following is a specification.

The essential features of this invention relate to improvements in the construction of the 10 tripod, its legs, joints, and the mechanism for securing the rock-drill stock to the same.

Other features relate to details in the construction, more fully understood from the description and claims hereinafter stated.

15 In the drawings hereto annexed, Figure 1 represents a top view of the tripod, the drill-stock fastening-plate being shown turned to hold the drill-stock while in a horizontal position. Fig. 2 is a vertical central longitudinal section of the same. Fig. 3 is a lateral vertical section centrally through the main hub, to which the legs are attached. Fig. 4 is a detached cross-section of one of the outer attached legs and its joint. Fig. 5 is a similar 25 lateral section at one of the inner leg-joints. Fig. 6 is a detached top view of the clamping-jaw of the drill-stock fastening. Fig. 7 is a lateral vertical section of the same. Fig. 8 is a detached top view of the clamping plate or 30 seat of the drill-stock. Fig. 9 is a detached side view of a portion of the drill-stock, to which the tripod is attached.

With the rock-drill, with a tripod constructed according to this invention, the drill-stock to 35 secure it to the tripod is formed with a flat circular base-plate or hub having a dovetail-shaped periphery, and the tripod has a dovetail stationary jaw and a movable clamping-jaw to grip the dovetail periphery of said hub 40 or base-plate.

A represents the portion of the drill-stock to which the tripod is attached, and B is the projecting dovetail-shaped or flanged hub, formed, cast, or secured thereon to attach the 45 stock to the tripod.

C represents the stationary jaw plate or seat for the hub B. It has the dovetail segmental projection e, to meet a portion of the periphery of the hub B.

50 D is the movable jaw to engage the opposite

portion of said hub B. Said jaw-plate C has formed on its lower side a lateral horizontal hub, E, with a bell-shaped end, f, on each extremity, and the plate C opposite its projection e is formed with a dovetail-shaped tongue, 55 d, over which the movable jaw D is closely fitted to slide with the dovetail groove e.

In order to powerfully press the jaw D against the hub B, a screw or screw-stud, F, is employed in the direction of the sliding motion and through the jaw D, and passing with its threaded end into the hub E, so that by turning said screw F in one direction the jaw is forced against the hub B, and turning it in opposite direction said jaw withdraws from 65 said hub, as clearly shown in Fig. 2. In the cavity of each bell-shaped end f is employed a closely taper-fitted journal or jointed hubs or plugs, G, which are both held into their respective bells f by means of a screw-bolt, H, 70 employed longitudinally and centrally through the hub E and said plugs G. Each said plug extends considerably from its bell, and upon said extending portion are employed the leg-connections in manner to allow the legs to turn 75 thereupon. I represents the central rear leg of the tripod, and J J are the two forward legs of the same. The legs J J, with their connection, are attached, respectively, each to the outer end of the respective plug G. The rear leg 80 has a forked top end or cross-head, K, of which each end terminates with a loop-shaped head, L, fitted closely over the periphery of the plug G, and a portion, g, from the inner periphery of said loop-head rearward is slotted to allow the 85 head to yield. A lateral screw-bolt, M, is employed through said loop-head, by means of which the same may be contracted to more or less grip around the periphery of the plug, as clearly shown in Fig. 5.

90 For each leg J is employed over the portion of the plug G a loop-strap piece, N, fitted closely upon the plug and having an outward-projecting round taper shank, O.

Each leg J has a bell-shaped head, P, which 95 is closely fitted over said taper shank O, and a radial screw-bolt, R, is employed which is secured with its head in the shank O and passes from said shank through the head P, as shown in Fig. 4. By means of said bolt 100

R the head P is caused to grip the shank O very tightly to prevent the leg to change position. After properly located by slackening the bolt R the leg is readily turned to put it in proper position. By means of the expanding jaw the drill-stock is very conveniently detached or attached and held solidly.

By means of the leg-joints and connection the tripod is readily adjusted to the ground 10 and solidly held in its position.

What I claim, and desire to secure by Letters Patent, is—

1. In a tripod for rock-drilling machines, the combination, with a dovetail or flanged 15 portion on the drill-stock, of a stationary jaw plate or seat provided with a dovetail segmental projection or jaw, a dovetail tongue projecting from the opposite side of the jaw-plate, a movable jaw provided with a dovetail groove to receive said tongue, a horizontal hub upon the under side of the jaw-plate, a screw-bolt passing through the movable jaw and entering said hub, and supporting-legs 20 jointed onto the hub, substantially as described.
2. In a tripod for drilling-machines, the com- 25

bination, with a jaw seat or plate and a horizontal hub upon the under side of the same, provided with bell-shaped ends projecting beyond the jaw-plate, of tapered or beveled plugs or hubs seated in said bell-shaped ends, a bolt 30 extending longitudinally through the horizontal hub and plugs and locking the same in the bell-shaped ends, a forked leg provided with loop-heads embracing said plugs, bolts or screws to tighten said loop-heads, a loop-strap 35 embracing each plug and provided with an outwardly-projecting shank, supporting-legs, a bell-shaped head upon each leg adapted to fit over the shanks upon the loop-straps, and a bolt passing through each shank and bell-shaped head, whereby the same are locked together, substantially as described.

In testimony that I claim the foregoing as my invention I have signed my name, in presence of two witnesses, this 15th day of April, 45 1887.

THOMAS JAMES MURPHY.
